UNITED STATES PATENT OFFICE.

HARRY N. TENNILLE, OF DUMBARTON, VIRGINIA.

PERMUTATION-PADLOCK.

1,342,033.

Specification of Letters Patent.

Patented June 1, 1920.

Application filed April 18, 1917. Serial No. 163,003.

To all whom it may concern:

Be it known that I, HARRY N. TENNILLE, a citizen of the United States, residing at Dumbarton, in the county of Henrico and 5 State of Virginia, have invented certain new and useful Improvements in Permutation-Padlocks, of which the following is a specification.

This invention relates to permutation 10 padlocks.

The primary object of the invention is to provide a permutation padlock provided with a plurality of annular tumblers associated with an improved locking mechanism 15 whereby the lock shackle may be released only upon placing the tumblers in a certain relative position, but which will permit the shackle to be placed into operative position, after being released, regardless of the position of the tumblers.

Another object of the invention is to provide a permutation padlock having a locking bolt pivotally suspended from the shackle and resiliently held in operative position, whereby tampering with the locking mechanism, through the medium of twisting 25 or pulling the shackle will be prevented.

Another object of the invention is to provide a plurality of rotatable tumblers carrying characters to be combined for forming a pre-determined combination, the tumblers being associated with a locking bolt within the barrel of the lock, whereby the same may be released upon the proper combination of characters being formed.

A further object of this invention is the provision of a permutation padlock which consists of comparatively few parts and is simple in construction, but durable and well 40 adapted to withstand the rough usage to which devices of this character are ordinarily subjected.

For a full description of the invention and the advantages and merits thereof, reference is to be had to the following description and the accompanying drawings, wherein is illustrated the preferred form 45 of my invention, in which;

Figure 1 is a side elevation of the lock constructed in accordance with my invention.

Fig. 2 is a longitudinal section there- through.

Fig. 3 is a detail perspective view of the 55 shackle and locking bolt.

Fig. 4 is a detail perspective view of one of the locking tumblers.

Fig. 5 is a transverse section on the line 5-5 of Fig. 2.

Fig. 6 is a similar section showing the locking bolt in unlocked position.

Referring to the drawing, wherein is illustrated the preferred form of my invention, and in which like numerals of reference indicate corresponding parts throughout the several views, the barrel 1 is of cylindrical formation and the same consists of the relatively large head 2 integrally connected with the cylindrical neck 3, the latter being of a diameter considerably less than the diameter of the head. A centrally located screw threaded recess 4 receives the screw threaded stud 5, carried by the cap 6 which forms the end of the barrel opposite to the head 2 and which is of the same general outline as the head.

Rotatably mounted upon the neck is a plurality of annular tumblers 7, 8, 9 and 10, the same being of identical construction, and slightly larger in diameter than the outer diameter of the head 2 or cap 6. These tumblers are in close frictional contact as shown by Figs. 1 and 2 of the drawing and their outer peripheries are provided with a plurality of characters, shown in the drawing as circumferentially spaced letters. One of these tumblers is shown in detail in Fig. 4 of the drawing, and it will be noted that the same is provided with an interior annular depression 11, thereby forming a relatively thin annular flange 12. The flange 12 in each tumbler has a notch 13, the bottom of which is flush with the annular wall of the depression. It will be obvious, therefore, that when the notches 13 in all of the tumblers are alined, a longitudinal passageway will be formed through the superposed tumblers. The character on each tumbler which is in radial alinement with the notch in the tumbler will, of course,

100 be the character which will form a part of the combination for the purpose of alining the notches. For instance, the notches in the tumblers 7, 8, 9 and 10 will be opposite the characters L, O, C, and K, respectively, 105 thereby forming the word "lock" as the key-word for forming the combination, whereby the notches may be alined for the purpose of unlocking the lock. It will be understood, of course, that any other com- 110

bination of letters may be employed to form the lock combination.

The head 2 is provided with a cavity 14 which merges into a longitudinal groove 15 formed in the neck 3. The cavity 14 also communicates with an opening 16, the latter opening receiving one end of the shackle 17. The opposite end of the shackle is received in a recess 18, formed in the top of the head 2, when the shackle is in locked position. The end of the shackle which projects through the opening 16 is slightly longer than the opposite end of the shackle so that its terminal is disposed considerably within the cavity 14. To this end of the shackle, a link 19 is pivotally connected and the opposite end of the link is fixedly connected to a locking bolt 20. The locking bolt is thereby suspended from the end of the shackle, and is permitted to be extended through the groove 15. The pivotal connection of the link with the shackle permits a rotary movement of the locking bolt around the end of the shackle, the latter acting as the axis for the locking bolt. The cap 6 has a recess 21 in communication with the groove 15, so that the end of the locking bolt may be projected into the recess 21, when the shackle is in locked position. It will be noted, however, that the distance the locking bolt projects into the recess 21 is substantially equal to the distance that the short end of the shackle projects into the recess 18, so that when this end of the shackle is withdrawn from the recess 18, the end of the locking bolt will also be withdrawn from its recess 21.

Referring particularly to Fig. 3 of the drawing, it will be noted that the locking bolt is provided with tangential recesses 22, longitudinally spaced thereby forming a series of equally spaced apart bits 22', the faces of which are beveled as clearly shown by Fig. 2 of the drawing.

Extending into the neck 3, and communicating with the groove 5, is an orifice 23, the same receiving one end of a coil expansion spring 24 adapted to engage the adjacent side of the locking bolt 20, thus forcing the locking bolt into engagement with the inner edges of the annular tumblers at the points where they pass through the groove 15, so that when the locking bolt is in locked position, the bits 22' will extend into the annular recesses in the tumblers and engage the flanges 12, thereby preventing withdrawal of the locking bolt and consequently preventing withdrawal of the shackle. When the tumblers are rotated, however, and the combination is set so that the notches 13 will be alined, the locking bolt may be drawn through the passageway, thus formed to permit the shackle to be released from the recess 18. The spring, of course, holds the locking bolt in close en-

gagement with the tumblers but permits the bolt to be longitudinally moved so that the shackle may be released. By virtue of the beveled faces of the bits 22', the bolt may be thrust back into locked position even though the tumblers have been turned so that the notches are in staggered relation. The beveled faces will simply slide over the edges of the tumblers against the compression of the spring, which later will force the bits into the recesses to obtain the locked position.

It is to be observed, also, that the extended end of the locking bolt received in the recess 21, prevents the removal of the cap 6 by unscrewing the stud 5, until after the shackle has been released and the bolt withdrawn from the recess 21. Suitable, longitudinally alined marks, designated by the arrows in Fig. 1, will be placed upon the surface of the barrel and cap 6 to permit the operator to determine at which point the characters are to be alined to form the combination.

A change in the combination is easily accomplished by unlocking the lock and unscrewing the stud 5, thus removing the cap 6. The tumblers can thereby be quickly removed from the neck 3 and replaced in any desired order to change the combination.

From the foregoing it will be observed that a very simple and durable lock has been provided, the details of which embody the preferred form. I desire it to be understood, however, that slight changes in the minor details of construction may be made without departing from the spirit of the invention or the scope of the claim hereunto appended.

I claim:

A lock comprising a cylindrical barrel, having a restricted neck and equipped with a head at one end and provided with a removable cap at its opposite end, a plurality of annular members rotatably mounted on the neck and held against displacement by the said cap, the said head and neck being provided with an interior longitudinal groove having a relatively large cavity at one end, a substantially U-shaped shackle having an elongated end adapted to be extended into the said cavity, the said head being provided with a relatively small recess to receive the opposite end of the shackle whereby movement of the shackle is prevented when in operative position, the said extended end of the shackle being received in the said recess and provided with a link pivotally connected to the end of the shackle and adapted for lateral swinging movement in the said cavity, a locking bolt attached to one end of the link and disposed to engage and disengage the said annular members as the said link is laterally swung in the said cavity, a spring ele-

ment having one end engaged with the said locking bolt to normally urge it into engagement with the said annular members, the portion of the locking bolt thus engaged being provided with bits having flat surfaces adapted to engage the annular members to prevent withdrawal of the locking bolt and beveled surfaces to facilitate insertion of the locking bolt, each of the 10 said annular members being provided with a notch adapted for alinement when the an-

nular members are in a predetermined position for providing a space whereby the said bits may be disengaged from the annular members to permit withdrawal of the 15 said locking bolt.

In testimony whereof I affix my signature in presence of two witnesses.

HARRY N. TENNILLE.
